UNITED STATES PATENT OFFICE.

GEZA D. BERKO, OF NEW YORK, N. Y.

DESIGN FOR A WATCH-CHARM.

48,343.

Specification for Design.

Patented Dec. 28, 1915.

Application filed May 11, 1915. Serial No. 27,466. Term of patent 3½ years.

To all whom it may concern:

Be it known that I, GEZA D. BERKO, a citizen of the United States, and a resident of the borough of Manhattan, city and State of New York, have invented a new, original, and ornamental Design for a Watch-Charm, of which the following is a specification.

My design is represented in the accompanying drawing, in which;

Figure 1 is a front and plan view of the watch charm illustrating my new invention. Fig. 2 is a rear plan view of the watch charm illustrating my new invention.

The design consists of an ornamental shape shown, having on one side the figure of a woman, representing the Patron Saint with a child in her lap and around the charm is lettering as shown. The obverse side of this charm bears a mottled surface with the inscription of 1914-1915 in the same and around the border letters in the Hungarian language as shown. The general effect of the charm is raised and may be colored as desired.

I claim:

The ornamental design for a watch charm as shown and described.

In testimony that I claim the foregoing as my own, I have affixed hereto my signature in the presence of two witnesses.

GEZA D. BERKO.

Witnesses:

GEZA KENDE,
E. W. ALEXANDER.
